WELL PACKER AND BRIDGE PLUG FOR
WELL BORESJohn R. Baker, Pasadena, and Martin B. Conrad,
Huntington Park, Calif., assignors to Baker Oil
Tools, Inc., Vernon, Calif., a corporation of
California

Application March 11, 1949, Serial No. 80,836

15 Claims. (Cl. 166—12)

1

The present invention relates to well packers adapted to be set in well bores, or in casings, liners and similar conduits located in well bores.

An object of the present invention is to provide an improved well packer or bridge plug, which is economical to manufacture, easily set in a well bore, and capable of withstanding substantial pressures when set in the well bore.

Another object of the invention is to provide an improved locking arrangement for securing packer or well tool parts in their set condition in a well bore. More specifically, the lock arrangement embodies a lock-device that enables the well packer to be made primarily of readily drillable materials, such as cast iron, magnesium, aluminum, and the like, and does not substantially distort such materials in preventing release of the packer from its expanded or set condition.

A further object of the invention is to provide a well packer, or well tool, embodying slips that are held initially in retracted position in a simple manner, and which cannot be shifted inadvertently to expanded position.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figures 1 and 1a together comprise a longitudinal section through a well apparatus disposed in a well casing, the parts of the apparatus being arranged for lowering through the well casing to the desired setting point, Fig. 1a constituting a lower continuation of Fig. 1;

Fig. 2 is a longitudinal section similar to Fig. 1a, disclosing the packer anchored in packed-off condition in the well casing;

Fig. 3 is an enlarged cross-section taken along the line 3—3 on Fig. 1a;

Fig. 4 is an enlarged cross-section taken along the line 4—4 on Fig. 2;

Fig. 5 is an enlarged fragmentary longitudinal section through the lock device of the well tool;

Fig. 6 is a cross-section taken along the line 6—6 on Fig. 1a.

The well packer A disclosed in the drawings includes an elongate central packer body 10 hav-

ing a lower guide and abutment 11 threaded, or otherwise attached, to its lower end, and an upper abutment 12 movably mounted upon its upper portion. A lower, circumferentially continuous slip sleeve 13 rests upon the lower abutment 11 and surrounds the upwardly projecting central boss 14 of the latter. This slip sleeve 13 is provided with an inner inclined surface 15 tapering upwardly and outwardly for cooperation with a companion tapered surface 16 on a lower frusto-conical expander 17 slidable along the body 10. The expander is preferably made hollow to reduce its mass, and may have inwardly directed spaced ribs or annuli 18 which slide along the body member.

A packing assembly 19, which is preferably of natural or synthetic rubber, encompasses the body and rests upon the upper end of the lower expander 17. Such end is provided with an annular step 20 supporting a flow preventing ring 21 having a substantially cylindrical external surface 22 and an upward and outwardly tapering inner surface 23, engaging a corresponding tapered surface 24 at the lower portion of the packing sleeve 19. The flow preventing ring 21 is of much harder rubber than the rubber of the packing material 19, so as to bridge the clearance space 25 between the expander 17 and the wall of the casing B in which the packer A is run, as an incident of setting the packer.

In a similar fashion, the upper end of the packing sleeve 19 engages the lower end of an upper frusto-conical expander 26, and also coacts with a hard rubber flow preventing ring 27 disposed around the upper end of the packing sleeve and received within an annular recess 28 in the upper expander. The upper expander 26 is also slidable along the upper portion of the packer body 10, and has an upward and inwardly tapering external surface 29 cooperable with a companion internal surface 30 on the interior of a circumferentially continuous upper slip sleeve 31 which engages the upper abutment 12. The inner end of the slip sleeve 31 encompasses a centering boss 32 depending from the upper abutment.

It will be noted from the drawings that the upper slip sleeve 31, upper expander 26, upper hard rubber bridging ring 27, and upper portion of the packing sleeve 19 are substantially identical with the corresponding parts at the lower portion of the well packer. However, the parts are oppositely arranged. In addition, it is to be noted that the upper slip ring 31 is provided with upwardly facing wickers or teeth 33 for em-

bedding in the wall of the well casing B, to prevent upward movement of the well packer A therewithin. The lower slip sleeve 13 is provided with downwardly facing wickers or teeth 34 for embedding in the casing wall, to prevent downward movement of the well packer therewithin.

The well packer A is set in the well casing B by moving the upper abutment 12 in a downward direction, and the body 10 and its lower abutment 11 in an upward direction with respect to each other. Since the slip sleeves 13, 31 are initially circumferentially continuous, they are designed to break into segments upon imposition of a predetermined wedging force thereon. Thus, each slip sleeve is of relatively thin section, and has inwardly extending longitudinal ribs 35 that cooperate with an associated expander 17 or 26. Relative longitudinal movement between each slip sleeve and its associated expander will cause the sleeve to be wedged over the expander and produce a fracturing or breaking of each sleeve at its thin wall sections 36 into separate segments 37, such segments being movable along the tapered surface of the expander and outwardly into engagement with the well casing B (see Fig. 4). Originally, the slips cannot expand, in view of their circumferential continuity.

The well packer A is run in the well casing to the desired setting point, whereupon the upper abutment 12 is shifted downwardly of the body 10, to wedge the upper slip sleeve 31 over the expander 26, producing fracture of the sleeve into a plurality of segments 36 and their engagement with the well casing. Inasmuch as these slip segments 36 are wedged between the upper expander 26 and the casing B, they cannot move downwardly to any further extent. The packer body 10 is then shifted upwardly, causing its lower guide and abutment 11 to move upwardly, carrying the lower expander 17 and lower slip ring 13 with it as a unit. During this motion, the lower expander 17 is moved toward the upper expander 26, shortening the packing sleeve 19 and expanding it outwardly into firm sealing engagement with the casing B. The hard rubber flow preventing rings 27 are also deformed outwardly into engagement with the casing b, forming a bridge between the expanders 17, 26 and the casing B, and preventing the relatively softer rubber material of the packing sleeve 19 from flowing through the annular clearance spaces 25 and retaining the packing sleeve in the position where it can perform its sealing function.

A continuation of the upward strain on the packer body 10 then wedges the lower slip sleeve 13 over the lower expander 17, effecting fracture of the sleeve into a plurality of separate segments, of the same general character as the upper slip segments 37, and their longitudinal upward movement along the lower expander, accompanied by their radial outward shifting into anchoring engagement with the well casing B, such as disclosed in Fig. 2.

The well packer A is retained with its slips and packing elements in their fully expanded positions by a lock device provided between the movable upper abutment 12 and the body 10. This lock device takes the form of an inherently contractible sleeve 38 of extended length located within an inner recess 39 in the movable abutment 12. The sleeve is provided with upwardly facing annular teeth 40 on its interior

engageable with the body 10, which may have a roughened exterior to insure digging in or biting of the ratchet teeth 40 with the body itself. The exterior of the sleeve is provided with upwardly facing annular teeth 41 engageable with companion downwardly facing teeth 42 formed in the movable abutment member.

For economy of manufacture, the internal lock ring teeth 40 may be formed as a buttress thread having upwardly facing transverse locking surfaces, and the roughened surface on the body may be provided by forming a companion shallow buttress thread 43 facing in a downward direction and of the same pitch as the internal ring thread 40. Similarly, the coengaging teeth 41, 42 on the exterior of the lock ring 38 and the interior of the movable abutment 12 may be formed as buttress threads of the same pitch.

As stated above, the well packer A is set by relative downward movement of the upper abutment 12 and upward movement of the body 10. Such relative movements can occur without interference, since the internal ratchet teeth 40 on the lock sleeve 38 merely ratchet over the corresponding ratchet teeth or roughened surface 43 of the body, without any substantial resistance to its movement. However, any tendency for the body 10 to move in a downward direction within the upper abutment 12, or for the upper abutment to move in an upward direction with respect to the body, is prevented by the locking engagement of the internal teeth 40 of the sleeve 38 with the roughened surface or teeth 43 of the body. In effect, the ring or sleeve 38 operates as a one-way coupling or clutch element, permitting relative upward movement of the body 10, but precluding its relative downward movement. Any tendency for the ring 38 to move downwardly with the body is resisted by wedging of the tapered cam faces 45 of its teeth 41 with the companion cam faces 46 forming the inclined surfaces of the buttress threads 42 in the movable abutment 12. Such wedging action urges the ring 38 inwardly into the body 10 with a greater force. It is preferred to make the bridge plug of readily drillable materials, in the event it is desired to remove it from the well casing after it has been set therein. Such materials may be cast iron, aluminum or magnesium, of which substantially all of the parts, with the exception of the packing assembly, are made. It is preferred to have the slip sleeves 13, 31 made of cast iron, regardless of the use of aluminum or magnesium for the other metallic parts of the well packer. Also, the lock sleeve 38 should preferably be made of some spring-like material, such as cast iron or steel.

In order to prevent bulging of the upper abutment 12 when it is made of comparatively soft, readily drillable material, such as magnesium, the slope of the coengaging cam faces 45, 46 is made much greater to the vertical, or longitudinal center line of the lock sleeve 38, than the slope of the ratchet tooth faces 47 internally of the lock sleeve. The internal faces 47 of the inner ratchet teeth make a substantial angle with the generally horizontal faces 48 of the teeth 40, so as to provide a strong tooth shape and allow relatively large forces to be transmitted in a downward direction between the packer body 10 and the lock sleeve 12. As an example, the acute angle at the edge of such tooth or thread 40 may be about 85 degrees; that is, the sloping face 47 of each tooth makes an angle of about 15 degrees

to the longitudinal center line of the lock sleeve 38.

If the coacting cam faces 45, 46 on the movable abutment ring 12 and lock sleeve 38 possessed the same steep angle as the inner ratchet teeth 46, the large downward forces on the body would be multiplied many times by the mechanical advantage afforded by the coacting cam faces, and would tend to bulge or break the movable abutment 12, especially if the latter were made of magnesium or other soft metal. For this reason, the sloping cam faces 45, 46 are inclined at a greater angle to the center line of the sleeve 38 and main abutment 12. As an example, the angle of inclination may be of the order of about 30 degrees. The greater angle of inclination to the longitudinal center line still insures the wedging of the ring 38 within the movable abutment 12 and its inward urging into firm engagement with the body 10.

It is to be noted that when the ring 12 is not under load, its external cam faces 45 have lateral clearance 48a with the companion cam faces 46 in the abutment ring. This arrangement permits the split sleeve 38 to expand outwardly when the movable abutment 12 moves downwardly along the body 10, or when the body moves upwardly within the abutment. Downward movement of the abutment causes its generally horizontal tooth faces 49 to engage the companion tooth faces 50 on the lock ring 38 and carry the latter downwardly along with it. Similarly, upward movement of the body 10 within the abutment 12 can occur without upward movement of the lock sleeve 38 because of the coengaging sleeve and abutment teeth faces 50, 49.

The initial circumferentially continuous condition of the slip sleeves 13, 31 and the relative stiffness of the rubber material of the packing assembly 19 will cause the parts to remain in their retracted positions during lowering of the tool in the well bore, as disclosed in Fig. 1a. As assurance against downward movement of the movable abutment 12, or relative upward movement of the body 10, during lowering of the well packer A in the well casing B, a shear pin or screw 51 may extend between the upper abutment 12 and the body 10. This screw 51 is disrupted when the well packer A is to be set.

The well packer may be set by any means which is capable of imposing a downward force on the upper abutment 12 and an upward force on the body 10. A setting tool C for performing this function is illustrated in Figs. 1 and 1a. This setting tool enables the entire apparatus to be lowered in the well casing on a wire line D.

The setting tool C includes a cylinder 55 having upper and lower heads 56, 57 threaded into the opposite ends of a cylinder sleeve 58. The upper head is threaded onto a cable head 59 secured to the wire line D in a known manner. Also threaded into the cable head is a gun barrel 60 containing a blank cartridge 61 connected electrically to the conductive core 62 of the wire line. This cartridge 61, when fired, ignites the upper end of a combustible charge 63, such as a railway flare, disposed within a combustion chamber 64 in the upper head 56. The combustible charge generates gases under pressure within the cylinder 55, forcing a piston 65 downwardly within the cylinder, or reactively elevating the cylinder itself.

The piston is secured to a depending piston rod 66 extending through the cylinder head 57 and into an elongate tubular mandrel 67 threaded into the lower head 57. The lower end of this man-

drel is threadedly secured to a coupling sleeve 68 that has an adapter 69 secured to it, into which the upper end of a disruptable tension stud 70 is threaded. The lower end of this tension stud is threaded into the upper end of the packer body 10. The tension stud has a reduced diameter medial portion 71 to insure pulling apart of the stud at this point, when the ultimate load capacity of the stud in tension is exceeded.

The piston rod 66 has a cross-piece 72 mounted in its lower slot 73, which extends in opposite directions from the rod through aligned elongate slots 74 in the tubular mandrel 67. The cross-piece extends beyond these slots and into aligned slots 75 in a setting ring 76, on which the upper end of a setting sleeve 77 is threadedly secured. This setting sleeve extends downwardly along the mandrel and has an adapter ring 78 secured to its lower end, to which an adapter sleeve 79 is attached, as by use of welding material 80. The lower end of this adapter sleeve bears upon a shoulder 81 of the movable abutment member 12.

Leakage from and into the cylinder 55 is prevented by suitable seal rings 82; whereas leakage along the piston 65 is prevented by the piston rings 63.

The well packer A, with its parts in retracted position, is secured to the setting tool C, and this combination is lowered on the wire line D within the well casing B to the desired setting point. When such point is reached, the blank cartridge 61 is fired electrically to ignite the upper end of this charge generates a gas capable of exerting a downward force on the piston 65 and piston rod 66, shifting them downwardly within the cylinder 55, and also moving the cross-piece 72, setting ring 76, setting sleeve 77, adapter ring 78 and adapter sleeve 79 in a downward direction. Such downward movement first disrupts the shear pin 51 and shifts the upper abutment 12 downwardly, as permitted by ratcheting of the lock sleeve 38 downwardly over the body 10, wedging the upper slip sleeve 31 over the upper expander 26. This wedging action breaks the slip sleeve 31 into segments 37 and enables such segments to be expanded outwardly into wedging engagement with the wall of the well casing B.

After such wedging engagement has occurred, the piston 65, piston rod 66, cross-piece 72, setting ring 76, setting sleeve 77, adapter ring 78, adapter sleeve 79, upper abutment 12 and slips 31 cannot move downwardly to any further extent. Further increase in the gas pressure in the cylinder 55, as a result of continued combustion of the charge 63, then causes the cylinder 55 to move upwardly, which exerts an upward pull on the tubular mandrel 67, tension stud 70, packer body 10 and the body abutment 11, in order to fore-shorten the packing sleeve 19 and expand it outwardly against the well casing B, as well as deform the flow preventing rings 21, 27 outwardly against the well casing.

Continued upward movement of the packer body 10 then wedges the lower slip sleeve 13 over the lower expander 17, breaking the sleeve into a plurality of segments, which are expanded outwardly against the casing B. As the pressure in the cylinder 55 continues to increase, a progressively greater upward force is imposed on the cylinder, tubular mandrel 67, tension stud 70 and body 10 to firmly and securely anchor the well packer A in packed-off condition within the well casing. When the tensile strength of the stud

10 is exceeded, it will be pulled apart at its reduced diameter portion 71, automatically releasing the setting tool C from the anchored bridge plug A. The setting tool may now be removed from the well casing by means of the wire line D (see Fig. 2).

Following release of the setting tool C from the well packer A, the latter will remain locked in its packed-off condition. Any tendency for the packer to move upwardly will be resisted by the 10 upper slips 31, since such upward force is transmitted from the lower guide and abutment 11, through the lower slips 13, lower expander 17, packing sleeve 19, upper expander 26 and upper slips 31 to the well casing B. Any tendency for 15 the well packer body 10 to move downwardly is resisted by the lower slips 13. This downward movement is transmitted from the body 10 through the lock sleeve 38 to the upper abutment 12, and from the upper abutment through the 20 upper slips 31, upper expander 26, packing sleeve 19, lower expander 17 and lower slips 13 to the well casing B.

It is accordingly apparent that a comparatively inexpensive well tool has been devised that can function as a well packer or anchor in a well bore. The parts are held in their initial retracted positions by themselves, and are readily expanded against the well casing when desired. After such expansion, they are retained in that condition because all of the parts are locked and wedged to one another and cannot be released. The locking arrangement is such as to enable the parts to be made of readily drillable materials, without bulging or becoming released inadvertently.

The inventors claim:

1. In a well tool: a body; an expander on said body; and a circumferentially continuous, frangible slip member engageable with said expander, said expander being movable longitudinally with respect to said slip member to exert a lateral force on said slip member to break said slip member into segments.

2. In a well tool: a body; an expander on said body having an external tapered surface; and a circumferentially continuous, frangible slip member having a tapered internal surface engageable with said external expander surface, said slip member being capable of being broken into segments by said expander upon relative wedging of said expander into said slip member.

3. In a well tool: a body; an expander on said body having an external tapered surface; and a circumferentially continuous, frangible slip member having circumferentially spaced ribs therewithin, said ribs being provided with tapered surfaces engageable with said external expander surface, said slip member being capable of being broken into segments by said expander upon relative wedging of said expander into said slip member, the regions where said member is broken lying between said ribs.

4. In a well tool: a body; an upper expander on said body having an external tapered surface inclined upwardly and inwardly; an upper circumferentially continuous, frangible slip member having a tapered internal surface engageable with said external surface; a lower expander on said body having an external tapered surface inclined downwardly and inwardly; a lower circumferentially continuous, frangible slip member having a tapered internal surface engageable with said lower expander external surface; each of said slip members being capable of being broken into segments by its companion expander upon rela-

tive wedging of said companion expander into its slip member; an abutment on said body engageable with one of said slip members; and another abutment slideable along said body and engageable with the other of said slip members; said abutments having bosses devoid of lateral projections extending within said slip members for centering said slip members with respect to said body.

5. In a well tool: a body; an expander on said body; slip means operatively associated with said expander; an abutment engageable with said slip means and slideable along said body in one direction to shift said slip means along said expander and outwardly into anchoring engagement with a well conduit; and lock means for preventing movement of said abutment relative to said body in the other direction, said lock means comprising a split sleeve having internal teeth engageable with said body, said sleeve also having external cam teeth engageable with companion internal cam teeth on said abutment to urge said sleeve internal teeth laterally inward into engagement with said body.

6. In a well tool: a body member; an expander on said body member; slip means operatively associated with said expander; an abutment member engageable with said slip means and slideable along said body member in one direction to shift said slip means along said expander and outwardly into anchoring engagement with a well conduit; and lock means for preventing movement of said abutment member along said body member in the other direction, said lock means comprising a split sleeve having inner and outer surfaces, ratchet teeth on one of said surfaces engageable with one of said members, and cam teeth on the other of said surfaces engageable with companion cam teeth on the other of said members to urge said ratchet teeth into engagement with said one of said members.

7. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split, inherently contractible sleeve having internal teeth engageable with said body, said sleeve also having external cam teeth engageable with internal cam teeth in said abutment to urge said sleeve internal teeth into engagement with said body.

8. In a well tool: a body member; normally retracted means on said body member; an abutment member engageable with said normally retracted means and slideable along said body member in one direction to shift said normally retracted means outwardly; and lock means for preventing movement of said abutment member along said body member in the other direction, said lock means comprising a split sleeve having inner and outer surfaces, ratchet teeth on one of said surfaces engageable with one of said members, and longitudinally spaced cam teeth on the other of said surfaces engageable with companion longitudinally spaced cam teeth on the other of said members to urge said ratchet teeth into engagement with said one of said members.

9. In a well tool: a body member; normally retracted means on said body member; an abutment member engageable with said normally retracted means and slideable along said body member in one direction to shift said normally retracted means outwardly; and lock means for

preventing movement of said abutment member along said body member in the other direction, said lock means comprising a split sleeve having inner and outer surfaces, ratchet teeth on one of said surfaces engageable with one of said members, and longitudinally spaced cam teeth on the other of said surfaces engageable with companion longitudinally spaced cam teeth on the other of said members to urge said ratchet teeth into engagement with said one of said members, the converging cam faces of said cam teeth making a substantially greater angle to the axis of the body member than the back faces of said ratchet teeth.

10. In a well tool: a body member; normally retracted means on said body member; an abutment member disposed above and engageable with said normally retracted means and slideable downwardly along said body member to shift said normally retracted means outwardly; and lock means for preventing relative upward movement of said abutment member along said body member, said lock means comprising a split inherently contractible sleeve having inner and outer surfaces, ratchet teeth on one of said surfaces engageable with one of said members, and cam teeth on the other of said surfaces engageable with companion cam teeth on the other of said members to urge said ratchet teeth into engagement with said one of said members.

11. In a well tool: a body member; normally retracted means on said body member; an abutment member engageable with said normally retracted means and movable along said body member in one direction to shift said normally retracted means outwardly; and lock means for preventing relative movement of said abutment member along said body member in the other direction, said lock means comprising a split sleeve having inner and outer surfaces, one of said surfaces having gripping engagement with one of said members, and longitudinally spaced cam teeth on the other of said surfaces engageable with companion longitudinally spaced cam teeth on the other of said members to urge said one of said surfaces into engagement with said one of said members.

12. In a well tool: a body member; normally retracted means on said body member; an abutment member disposed above and engageable with said normally retracted means and slideable downwardly along said body member to shift said normally retracted means outwardly; and lock means for preventing relative upward movement of said abutment member along said body member, said lock means comprising a split sleeve having an inner surface capable of gripping said body member, said split sleeve having longitudi-

nally spaced cam teeth on its outer surface engageable with companion longitudinally spaced cam teeth on said abutment member to urge said inner surface into engagement with said body member.

13. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

14. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

15. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

16. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

17. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

18. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

19. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

20. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

21. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

22. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.

23. In a well tool: a body; normally retracted means on said body; an abutment engageable with said normally retracted means and slideable along said body in one direction to shift said normally retracted means outwardly; and lock means for preventing movement of said abutment along said body in the other direction, said lock means comprising a split sleeve having internal teeth engageable with said body, said sleeve also having an external helical thread meshing with a companion internal helical thread in said abutment to urge said sleeve inwardly into engagement with said body.
